UNITED STATES PATENT OFFICE

WILLIAM TRENT RAGLAND, OF RALEIGH, NORTH CAROLINA

METHOD OF MIXING PAVING MATERIAL

No Drawing.

Application filed December 31, 1925. Serial No. 78,699.

The present invention relates to a method of mixing paving material, and, in the present disclosure, it will be described in connection with bituminous paving material.

5 Paving materials, and, particularly, the type in which a bituminous binder is used, are ordinarily composed of an aggregate and a suitable binder, such binder, in the bituminous type of pavement, being a mineral pitch. 10 In mixtures of this character, it is essential to a stable and wear-resisting pavement, that the aggregate and binder be brought into intimate relation, and that the particles of aggregate be thoroughly and completely coated 15 and impregnated with the binder. Failure to do this will result in uneven areas or zones throughout the material where uncoated or insufficiently coated particles of the aggregate are found, and this condition of the 20 material gives an unsatisfactory pavement, for the reason that there will be, throughout the pavement, areas of material, which, because they are not sufficiently bound together, will break up under traffic strain, or disintegrate under the action of the elements. 25

Paving material of this general character is ordinarily produced by mixing the aggregate, which is composed of different sizes or 30 grades of material, usually running from the filler dust up to larger fragments of a size suitable to the work in hand, with a mineral pitch, where a bituminous pavement is to be made, and this mineral pitch or bitumen, together with the aggregate, is manipulated to 35 bring about a coating and impregnation of the aggregate by the pitch.

It has heretofore been customary to select 40 and grade the aggregate, then mix that aggregate, which is, preferably, thoroughly heated to drive off the moisture and expand the particles, and to such aggregate mixture the binder is then applied, and the mass is then tumbled or agitated, with a view of coating the individual particles of the aggregate with 45 the binder.

While paving mixtures, prepared in accordance with this plan, have merit, this method of mixing has been found defective, for the reason that where the different sizes 50 of aggregate are intermingled before the

binder is applied, there is a tendency of the larger particles of the aggregate to rob the smaller particles of the binder, and, particularly, to deprive the finer grades, especially the dust or filler, of proper impregnation 55 with the binder. It has been found that under the old method, the finer grades of material, particularly the dust or filler, will ball up in the interstices between the larger particles of the aggregate, and the binder 60 will be prevented from getting to and coating and impregnating the fine, individual particles of the smaller sizes of aggregate. This inevitably results in a mixture which, because of insufficient and imperfect coating, 65 contains weakened and unbound areas, which, when laid in a pavement and exposed to the stresses of traffic and the attacks of the weather, will quickly disintegrate and 70 break down.

It is with a view of providing a method by following which the complete coating and impregnating of all of the particles of aggregate, from the filler dust to the larger 75 sizes, will be secured, and a mixture, free from faulty and weakened areas, produced, so that, when laid, a pavement of uniform character and great stability will be produced, that I have devised the present method of mixing aggregate and binder. 80

The method may be practiced with any 85 of the well known types of apparatus now in use, such as mixers of the pug mill, rotary, or tumbler type, and this being the case, it is unnecessary to illustrate any specific apparatus for carrying out my new and improved method.

In practicing the method which I have invented, the aggregate will first be selected 90 from appropriate material and graded into the desired sizes, it being common to grade material which is to form the aggregate from the filler dust up to material of approximately one and one-half inch mesh in size. These various grades of material will be kept separated, one from the other, and, as is usual, will be subjected to heat of sufficient temperature to thoroughly dry them, and to expand the particles so as to put them 95 100

in condition for receiving and absorbing the coating and impregnating binder.

After the aggregate has been prepared, the binder will be put into the mixer of 5 whichever type is selected, and if the binder is of the mineral pitch type, it will, preferably, be heated so as to be in liquid form in the mixer. The aggregate is then introduced in any suitable manner, by delivering 10 to the mixer and the binder therein, the different grades, and this introduction of the successive grades of aggregate will be effected while the binder is being agitated in the mixer, so that as the successive grades are 15 introduced, each grade will, in succession, be subjected to a coating action. The mixing step will continue after the introduction of one grade of aggregate, until that grade has been thoroughly coated and impregnated; 20 then another grade of aggregate will be introduced, and the mixing operation continued until that succeeding grade has been thoroughly coated, impregnated and intermingled with the mass already in the mixing 25 apparatus. By thus successively introducing and thoroughly mixing each grade as it is introduced, it will be seen that the particles of aggregate under treatment in the mixer at any one time will all be of uniform size, 30 and the tendency of the larger sizes to deprive the smaller sizes of the binder, which is present where the aggregate is introduced in a mixed mass, is eliminated, the particles of uniform size, where they are successively 35 introduced, each having an equal opportunity to take up and coat and impregnate themselves with the binder. The particles already coated will not interfere with the uniform coating of the next succeeding grade 40 of aggregate introduced, for, since the particles of aggregate first introduced have been thoroughly intermixed, and have received their share of the binder, the uncoated particles of the succeeding grade will equally 45 and uniformly take up their share of the binder.

I have found that, preferably, the aggregate should be introduced into the binder in the mixing apparatus by introducing first the 50 fine aggregate or filler dust, and then proceeding regularly through the other grades, with the next grade in order of fineness, although it is conceivable that under some conditions, the order of introduction might 55 be reversed or varied.

The reason for introducing the filler dust or fine aggregate first, is that this has a tendency, under the methods now in use, to agglomerate or ball up, so that it will appear 60 in the mixture in the form of coated pellets or small masses, which will be held by an envelope of binder, but with their interiors uncoated, and, consequently, unstable and friable. This condition, obviously, interferes with the stability of the mixture, and 65

produces weak and faulty areas, which are readily disintegrated under traffic strains and by the attacks of the weather. By introducing the filler dust or fine aggregate initially 70 into the binder, and subjecting it to the thorough mixing action of the apparatus, the small particles will be individually coated and impregnated. A much better result is obtained than under the old method, for with the filler dust being manipulated by itself 75 in the mixing apparatus, in the presence of the binder, its commingling with the binder is in no way interfered with by larger particles of aggregate, and there is no robbing 80 of the small particles of their proper proportion of binder.

When the filler dust has been thoroughly commingled with the binder, the next coarser grade will then be added, and it will take up its proper proportion of the binder, and the coating and impregnating of this next grade will not be interfered with by the already coated finer grade first introduced. This same condition will obtain for each 85 succeeding grade, for there is not at any time in the mixer, uncoated aggregate of different grades, one of which grades, namely, the larger one, has a tendency to deprive 90 a smaller grade of its proper share of the binder.

The aggregate may be introduced in any suitable or approved manner, but, preferably, it will be conveyed to the mixing apparatus and the binder therein in a diffused and scattered condition, so that it will not be dumped, 100 as a mass, into the binder, but will be delivered to it with the particles separated from one another. This introduction of the aggregate in diffused and separated condition may be accomplished by any suitable scattering devices capable of delivering the aggregate to the mixer in a scattered condition. This could be done by delivering it down 105 an inclined plane under the force of gravity, suitable scattering devices being provided to separate the stream of aggregate. It could be delivered by a suitable screw conveyor, having at its delivery end a scattering wheel, which would throw the aggregate over a 110 considerable area and shower it into the mixing apparatus. It can be projected in a shower, by a sand scattering belt of familiar design.

I have found, however, that it may readily be conveyed, by air through a suitable pipe, having orifices of sufficient size 115 to handle the largest grade of aggregate, through which the aggregate is expelled, the only thing necessary being that a scattering of the aggregate, as distinguished from throwing it in in masses, be provided for. It is conceivable that a skillful workman could introduce it in properly scattered form, by so manipulating a shovel as to properly 120 broadcast the shovel load.

I claim:—

1. The method of mixing paving material, which consists in depositing in a suitable mixing apparatus a substantially liquid binder, 5 blowing into said mixing apparatus and to said binder in diffused and scattered condition the different grades of aggregate, and agitating the mixture of binder and aggregate upon the introduction of each grade of 10 aggregate.

2. The method of mixing paving material, which consists in depositing in a suitable mixing apparatus a substantially liquid binder, blowing into said mixing apparatus and to 15 said binder in successive order of fineness and in diffused and scattered condition the different grades of aggregate, and agitating the mixture of binder and aggregate upon the introduction of each grade of aggregate.

20 In testimony whereof I have hereunto set my hand.
